PROCESS OF PRODUCING STENCILS

Edward O. Norris, Westport, Conn., assignor to
 Edward O. Norris, Inc., New York, N. Y., a corporation of New York

Application June 5, 1941, Serial No. 396,681

11 Claims. (Cl. 204—11)

This application is a continuation-in-part of my co-pending application Ser. No. 376,769, filed January 31, 1941, now Patent No. 2,282,203, May 5, 1942.

The invention relates to screen stencils such as are used for making ink and paint impressions of designs, depositing adhesive in the form of a design for flock-printing, applying dyes to form a design, and in general making impressions of a large variety of materials. More particularly, it relates to processes of producing stencils of the general character just described, so constructed that fine lines of the design to be impressed or printed are clearly defined and unbroken, and the edges of larger areas are clearly demarcated and free from the ragged or "saw-tooth" appearance which often characterizes work done with the ordinary screen stencil.

The objects will be presently more clearly brought out as the stencil itself and the mode of constructing it are explained in connection with the drawings.

Referring to the drawings,

Fig. 1 is an isometric view showing a portion of stencil base which consists preferably of electroformed foraminous sheet. On the sheet is indicated an area in the form of an annulus which may be taken for purposes of illustration as the design that is to be printed or impressed;

Fig. 2 is an isometric view showing the foraminous sheet of Fig. 1 covered with two successive layers of material in association with a printing plate;

Fig. 3 is an isometric view showing the design blocked out;

Figs. 4 and 5 show successive steps in the process;

Fig. 6 shows a completed stencil;

Figs. 7-12 show a modification of the process.

It is to be realized that the drawings are on a vastly larger scale than would be employed in practice. Usually the base screen would have in the order of from 25 to 100 meshes to the linear inch, and as much as possible of the area would be open, the limit of open area obviously being fixed by the strength of the material, the nature of the use to which the stencil is to be put, etc. In most cases the design would be of a more elaborate nature than what I show in the drawings. However, the principle involved in my invention is the same regardless of the elaborateness of the design, and so I have selected a very simple one by which to explain the process and the final product.

Referring specifically to the drawings,

Fig. 1 shows a portion of an electroformed screen consisting of the wires 10 intersected normally by the wires 11. Preferably, as stated above, the open areas 12 are as large as possible consistent with suitable structural strength. Such a screen and a method of producing it by electroforming on a matrix are illustrated and described in my United States Patent No. 2,166,366 issued July 18, 1939, and therefore it is not necessary at present to go into details as to how the screen itself is produced.

In using the term "wires" to describe the component parts of the screen structure, I am aware that the word is used in a sense somewhat beyond the usual. However, it is a fact that a true wire structure, such as woven wire screen, would serve my purposes, although, as I have found, not as satisfactorily as does the electroformed screen. In screen of the electroformed type, what I have termed "wires" are frequently known as "lands." In general, such screen structures may be termed "mesh fabric," which includes, in the ordinary accepted meaning of the term, not only woven fabric but also that which is punched, etched or electroformed as well.

To make the process clear, I have shown on Fig. 1 in dotted lines an annular area which will correspond with the open area of the completed stencil, the remaining areas of the stencil of course being blocked out, as will be presently described, by imperforate sheet superimposed thereon.

In order to make clear the description, it should be explained that it involves selective etching—i. e., the employment of etching agents that corrosively react on one material to the exclusion of another, and to avoid complicated language it will be assumed that the material of the base screen is of nickel. On the nickel screen which will eventually serve as a backing for the layers of imperforate material to be laid thereon, is deposited a layer 13 of copper, the copper completely covering the base screen itself to a substantial thickness. This copper is applied preferably by electroplating, the "bottom" (with reference to the orientation of the screen as shown in the drawing) being suitably masked by covering with waxed paper or according to other methods well-known in the electroplating and electroforming arts. As an incident to the electroplating step (unless the holes are first filled with electrically non-conductive material), the copper not only overlies the base screen but 55 it also extends into the holes. As will be ap-

parent however, as the description goes on, it is merely necessary that the copper overlie the screen.

The next step consists in applying to the copper layer the light-sensitive layer 20 of photo-engraver's glue, or light-sensitized shellac. The well-known coatings known as "Coldtop" and "Gluetop" also serve the purpose very well. The particular type of coating is not, however, important, provided that when developed it is passive to electrolytic deposition and is not deleteriously affected by the electrolyte which will be employed in a subsequent step, as will be later explained.

The next step (see Figs. 2 and 3) is to photo-print the design on the coating of light-sensitive material, which is accomplished by means of the plate 16 exhibiting a negative of the design indicated by the numeral 23 (Fig. 2). In other words, the shaded portion of the plate is opaque to light, and the design to be subsequently printed by the stencil is transparent. The printing being completed, the result is that the area of the light-sensitive coat protected by the shaded area of the plate 21 from the light source is unaffected while the remaining area—i. e., the design—is hardened and insoluble to water. The light-sensitive coat is then "developed" by washing in water if the "Gluetop" is used, consequently exposing the copper as shown in Fig. 3, where previously covered by the opaque area. If shellac be used, the developing could be carried out with an alcoholic preparation sold under the tradename of "Chemco Glascote Developer." The steps of blocking out the design on the copper are well-known and need no detailed or further description. It might be added, however, that the developed coat 24 that blocks out the design should preferably be further hardened by baking.

A step that may be carried out at this stage, although it could as well be carried out at any time after the copper layer 13 has been deposited, consists in applying to the bottom of the screen a very thin layer 30 of nickel which covers the screen itself as well as the copper and forms webs, bridging the apertures in the screen. It should be noted that the term "very thin" is used relatively in comparison with the mesh number of the screen, its thickness, and the thickness of the copper layer—for example, in the case of a 100-mesh screen (100 screen units to the linear inch), and with the screen itself .005" thick and the copper the same, the thickness of the layer could properly be in the order of .00005". The same proportions would serve as the screen units per linear inch were increased or decreased from the assumed number. The important thing is that its strength shall be sufficient to withstand the handling to which the structure will be subjected in the course of applying a heavy layer of nickel presently to be referred to; on the other hand, it should preferably be no thicker than is sufficient to serve this purpose since, as will further appear, it should be possible to etch it quickly through without removing any substantial amount of material from the rest of the structure. The thin layer 30 having been applied, the structure of Fig. 3 is subjected to a copper etching process whereby the copper 13 is etched away except insofar as it is protected by the band of solidified glue or other blocking-out material 24—i. e., the etching is arrested when the copper has been slightly undercut beneath the marginal areas of the glue but before the wires of the screen have been

reached. These results can be accomplished with a sufficient degree of accuracy by properly adjusting the thickness of the copper layer with respect to the width of the band of glue and with respect to the width and height of the screen wires. In other words, if the band of glue be excessively narrow, the etchant will reach the screen wires before the copper has been undercut or sufficiently undercut beneath the glue band, and, as will become obvious, after the full process has been explained, it would then not be possible to etch the ink-feeding passages from one face of the stencil to the other. A suitable etchant for the combination of materials that have been specified by way of example, is chromic acid inasmuch as, although it readily etches the copper, it does not affect the band of hardened glue nor the material of the screen nor the layer 30 of nickel. There is then applied by electro-plating a heavy deposit 31 of nickel. This deposit covers the wires of the screen, the areas of the layer 30 that are exposed between the meshes of the screen with or without a residual layer of copper dependent upon the stage at which the copper etching step has been arrested, and also what is left of the copper layer 13 beneath the band of glue; and its upward growth is limited by the overhang of the latter. The thickness of this heavy deposit is such as to give it the necessary strength to withstand the printing pressures to which the stencil will be subjected in actual use without collapsing and blocking the ink passages which will subsequently be opened up. This point will become clear as the description proceeds.

The heavy deposit of nickel having been applied, the band 24 of the developed glue is removed by the application, for example, of caustic potash, and then what is left of the copper layer 13 or most of it is etched out by chromic acid which has no effect or substantial effect on the nickel deposit 31. This operation opens up passages through to the thin layer 30 of nickel. After removing the thin nickel layer 30, which may be done by brushing, the result is shown in Fig. 6, where, as it will be observed, the fine line of the design is not blocked against the passage of ink by any of the wires of the screen. The layer 30 may also be removed by anodic treatment in a dilute sulphuric acid bath, which operation is promptly arrested when passages have been completely opened up from the design areas around the wires of the screen to its rear face. The object of making the nickel layer 30 as thin as possible is now obvious. Its only purpose is to serve as a base in the apertures of the screen on which to deposit the heavy nickel layer 31. Therefore, it need be no thicker nor stronger than is necessary to serve this purpose and to withstand the handling that is necessary in applying the heavy nickel layer 31. The thinner it is, the more easily may it be brushed off to open up the passages referred to; also, the thinner it is in comparison with the thickness of the heavy nickel layer 31, the sooner the anodic treatment may be arrested and the less will be the amount of material removed from the heavy layer.

In applying the several layers of metal, electroplating acts satisfactorily. Where etching is referred to, electrolytic deplating is included wherever the process is applicable.

The advantages of the stencil can now be brought out more clearly than before. By referring back to Fig. 1, it will be seen that, when the design includes fine lines such as the annular figure which I am using as an illustration, the

ordinary process of simply blocking out the stencil to form the design leaves these fine lines in many cases overlying and blocked by portions of the lands. This may be illustrated by reference to Fig. 1, where, for example, a portion of the design traverses for a short distance the land 11^a as indicated. It also crosses various other lands and is blocked out by the land 11^a . Consequently, when a stencil of the simple form just referred to is used for printing fine line figures, especially where the lines are about the width of a screen unit or less, the lines, when printed, appear broken for the reason that the ink is not delivered at those portions where the design is blocked out by the screen lands. By the term "screen unit" is meant the linear dimension of a wire and an adjacent aperture combined. My stencil, however, is distinguished from the standard construction which I have described in that in the former the fine line discharge orifice for the ink is open at all points to the source of supply on the opposite or rear side of the stencil, and thus the ink or the like comes through freely, passing around the wires of the screen and thence through the discharge orifice in uniform volume and in an unbroken stream. As an extension of the foregoing, the stencil also has definite advantages even where an area covering many apertures of screen is open, in that the edges of the printed design do not present a ragged or saw-tooth appearance as they would and do where access of ink to them is partially obstructed by the screen lands.

In explaining the invention I have up to this point preferred, for the sake of clarity, to name a specific combination of materials in describing how it may be carried out. However, it will be seen that the underlying principles do not necessarily involve the use of the specific materials that I have named; for example, if the base screen and the layer 30 were of copper instead of nickel, the layer 13 could be of zinc instead of copper. In such case, obviously the choice of etching agents would need to be adapted to bring about the selective actions that are necessary in the case just supposed; for instance, the etchant for the zinc could be dilute sulphuric acid since dilute sulphuric acid does not react on copper although it actively reacts on zinc. The etchant for the zinc should also be of such a character that the developed light-sensitive coating area 24 is passive to it; likewise, the light-sensitive coating 24 should be passive to the action of the electrolyte whereby the zinc is deposited.

If other combinations of metals than suggested above or other types of sensitized coating are used, it is necessary to select etchants that will act selectively in accordance with the foregoing principles. As to the combination of nickel and copper, I have selected them as preferable because they are adaptable for stencil purposes, are readily etched selectively, are comparatively inexpensive, and lend themselves readily to the electroforming process.

Figs. 7-12 show a modification of the process of the previous figures.

Referring to Fig. 7 there is shown, in dotted lines, a cathode matrix of the type hereinbefore referred to and which may comprise a metal plate 40 one face of which is provided with a multitude of pits filled flush with the surface with electrically non-conductive material 41 , such as Bakelite, the surface therefore comprising a multitude of electrically non-conductive areas delimited by crossed lanes of conductive

areas, these lanes corresponding in pattern to the pattern of the screen to be produced. Prior to the electroforming step the screen is covered with a stripping layer—e. g., wax, which is applied in such a thin coat that, while it does not prevent electrodeposition, it does render the entire surface of the matrix non-adherent thereto. The matrix being thus prepared, there is electroformed on it a screen of nickel indicated by the numeral 42 , and thereupon and before the electroformed screen is stripped, its interstices or apertures are filled with a plastic substance 43 , such as wax. Any surplus wax of which, of course, there will always be some is then rubbed off until the crowns $43a$ of the screen wires are exposed and free from it. The entire surface is then smeared with finely divided graphite (flockulent graphite being a desirable form) which renders the surfaces of the plastic fillings electrically conductive and capable of taking an electroplated deposit. The surface is then brushed to remove any graphite that lies on the crowns of the screen wires in order that they also may be capable of receiving an adherent electroplated deposit. There is then electroplated on the surface thus prepared a heavy layer 44 of copper.

The structure thus formed is then stripped from the matrix and the wax and graphite washed out with acetone or other solvent accompanied by brushing and scrubbing. The stripped structure with the wax removed is then used as a cathode in a nickel electroplating bath (the surface of the copper having been properly masked by the application of a resist in accordance with well-known methods), the result of which is that the wires of the screen and the areas of the copper layer exposed by the removal of the wax are covered with a layer of nickel 47 which forms webs closing the apertures in the screen. This layer of nickel for reasons that will presently become apparent is very thin. In case, for example, of 100-mesh screen (100 screen units to the linear inch) and with the screen itself $.005''$ thick, the thickness of the layer could properly be in the order of $.00005''$. The same proportions would serve as the screen units per linear inch are increased or decreased from the assumed numbers.

The next step (see Fig. 9) is to apply a light-sensitive layer of photo-engraver's glue or light-sensitive shellac to the surface of the copper and, after the design 45 has been photoprinted thereon and developed in accordance with well-known methods, the structure of Fig. 9 is subjected to the action of an etchant which does not affect the glue or the nickel but does etch the copper. A suitable etchant is diluted chromic acid inasmuch as it answers the requirements just referred to. In brief, the photoprinting process may be similar to that described with respect to the first described process. If photo-engraver's glue is used, it should be hardened by baking in the usual way.

The result of the copper etching process is shown in Fig. 10 where the design in glue is supported by a ridge 46 of copper. This ridge conforms to the design in relief. The etching process is preferably carried to the point at which the copper is slightly undercut beneath the marginal areas of the glue but extends on both sides out over the thin layer 47 .

The structure of Fig. 10 is then electroplated with a heavy coating 49 of nickel, the parts not to be plated (i.e., the underside of the copper and the screen) being properly masked with a resist.

The glue (if glue be used) is then removed by the application of caustic potash and the copper ridges 46 etched out with chromic acid, resulting in the structure of Fig. 11. After removing the resist that has been employed in the previous step, the entire structure is treated anodically in a dilute sulphuric acid bath which results in etching the thin nickel layer, which procedure is arrested when passages 50 from the design area 51 around the wires of the screen and to its rear face have been opened up. As in the case of the nickel layer 30 of the first process described, the purpose in making the nickel layer 47 as thin as possible as compared with the heavy layer 49 is so that the passages referred to may be opened up before any substantial amount of material has been removed from the heavy nickel layer. As in the case of the nickel layer 30 first described herein, the only function that the thin nickel layer 47 performs is that of a base upon which the heavy layer 49 of nickel may be electroplated, and therefore the layer 47 need be no thicker nor stronger than is necessary to serve this purpose and to withstand whatever handling is necessary before the heavy layer has been deposited.

As in the process first described (Figs. 1-6), other combinations of metals and light-sensitive material may be adopted, provided they lend themselves to the principles of selective etching that have been hereinbefore stated.

I have described above certain methods of practicing the invention, including a preferred method, but I wish it to be understood that these methods are illustrative and not limitative of the invention and that still other methods can be practiced, including varying the order in which the several steps shall be carried out, and such variations still fall within the spirit and scope of my invention as set forth in the claims.

I claim:

1. The process of producing a stencil, which comprises closing the apertures in a nickel screen with thin webs of nickel, electroplating on the surface of the webs and the screen lands an unbroken heavy layer of copper, applying to the layer of copper a design in baked photographer's glue, etching the copper until it is undercut beneath the marginal areas of the design, electroplating a thick layer of nickel on the areas exposed by the etching step thereby adding a continuous metal layer to the surfaces delimited by the design areas, removing the glue, etching away the copper left unprotected by the removal of the glue, and then etching the entire structure until ink-feeding passages have been opened from the design areas of the heavy layer of nickel through the thin layer of nickel to the rear face of the screen.

2. The process of producing mesh fabric stencil, which comprises superimposing on one face of a sheet of nickel screen a solid layer of copper, blocking out a design on said layer of copper by the application of a coating of material passive to electrolytic deposition, applying to the opposite face of the screen a solid thin layer of nickel, etching the copper layer until the portions not covered by the blocking-out coating are slightly undercut beneath the blocking-out coating, electroplating a solid layer of nickel on the surface exposed by the etching operation thereby adding a continuous metal layer to the surfaces delimited by the design areas, removing the blocking-out coating, etching the portions of the copper layer remaining after the before-mentioned

etching operation until they have been entirely removed, and then removing the thin layer of nickel.

3. The process of producing mesh fabric stencil, which comprises superimposing on one face of a sheet of nickel screen a solid layer of another metal active to an etchant to which the screen is passive, blocking out a design on said superimposed layer by the application of a coating of material passive to electrolytic deposition, applying to the opposite face of the screen a solid thin layer of metal passive to said etchant, etching the superimposed layer until it has been slightly undercut beneath the blocking-out coating, electroplating a solid layer of metal likewise passive to said etchant on the surface exposed by the first-mentioned etching operation thereby adding a continuous metal layer to the surfaces delimited by the design areas, removing the blocking-out coating, etching the portions of the superimposed layer remaining after the said etching operation until they have been removed, and then removing the layer on the said opposite face of the screen.

4. The process of producing mesh fabric stencil, which comprises superimposing on one face of a sheet of nickel screen a solid layer of another metal active to an etchant to which the screen is passive, blocking out a design on said superimposed layer by the application of a coating of material passive to electrolytic deposition, applying to the opposite face of the screen a solid thin layer of nickel, etching the superimposed layer until it has been slightly undercut beneath the blocking-out coating, the thickness of said superimposed layer being so adjusted that when the undercutting is completed the great part of the material of said layer not protected by the coat will be removed, electroplating a solid layer of metal likewise passive to said etchant on the surface exposed by the first-mentioned etching operation thereby adding a continuous metal layer to the surfaces delimited by the design areas, removing the blocking-out coating, etching the portions of the superimposed layer remaining after the said etching operation until they have been removed, and then removing the layer on the said opposite face of the screen.

5. The process of producing mesh fabric stencil, which comprises superimposing on one face of a sheet of nickel screen a solid layer of another metal active to an etchant to which the screen is passive, blocking out a design on said superimposed layer by the application of a coating of material passive to electrolytic deposition, applying to the opposite face of the screen a solid thin layer of metal passive to said etchant, etching the superimposed layer until the portions not covered by the blocking-out coating are at least nearly all removed, electroplating a solid layer of nickel on the surface exposed by the first-mentioned etching operation thereby adding a continuous metal layer to the surfaces delimited by the design areas, removing the blocking-out coating, etching the portions of the superimposed layer remaining after the said etching operation until they have been removed, and then removing the layer on the said opposite face of the screen.

6. The process of producing mesh fabric stencil, which comprises superimposing on one face of a sheet of nickel screen a solid layer of another metal active to an etchant to which the screen is passive, blocking out a design on said superimposed layer by the application of a coat-

ing of material passive to electrolytic deposition, applying to the opposite face of the screen a solid thin layer of metal passive to said etchant, etching the superimposed layer until it has been slightly undercut beneath the blocking-out coating, the thickness of the said superimposed layer being so adjusted that when the undercutting is completed the greater part of the material thereof not protected by said coating will have been removed, electroplating a solid layer of nickel on the surface exposed by the first-mentioned etching operation thereby adding a continuous metal layer to the surfaces delimited by the design areas, removing the blocking-out coating, etching the portions of the superimposed layer remaining after the said etching operation until they have been removed, and then removing the layer on the said opposite face of the screen.

7. The process of producing mesh fabric stencil, which comprises superimposing on one face of a sheet of metal screen a solid layer of another metal than that of the screen, blocking out a design on said layer by the application of a coat of material passive to electrolytic deposition, applying to the opposite face of the screen a thin second solid layer of metal, etching the first-mentioned layer until the portions not covered by the blocking-out coat are substantially all removed, electroplating on the surface exposed by said etching a third layer of metal thereby adding a continuous metal layer to the surfaces delimited by the design areas, etching away the portions of the first layer remaining after the first etching operation until the said portions are entirely removed, and then removing the second layer, the metals of the several layers, the etchant, and the blocking-out material being so chosen that the etchant has a selective action on the metal of the second layer to the exclusion of the metal of the screen of the second layer and the blocking-out material, and the blocking-out material is passive to the action of an electrolyte from which the metals of the second layer and the third layer are deposited.

8. The process of producing mesh fabric stencil, which comprises superimposing on one face of a sheet of metal screen a solid layer of metal different from that of the screen, one of the metals being active to an etchant to which the other is passive, blocking out a design on the superimposed layer by coating with material likewise passive to said etchant and also to electrolytic deposition, applying to the other face of the screen a solid layer of metal also passive to said etchant, etching away the superimposed layer over those areas not covered by said coating, electroplating a layer of metal over the area exposed by the etching operation thereby adding a continuous metal layer to the surfaces delimited by the design areas, removing the coating and by means of said etchant etching the material of the superimposed layer remaining after the first etching operation and underlying the design area from which the coating has been removed, and removing the layer that has been applied to the said other face of the screen.

9. The process of producing mesh fabric stencil, which comprises superimposing on one face of a sheet of metal screen a solid layer of metal different from that of the screen, the metal of the superimposed layer being active to an etchant to which the screen is passive, blocking out a design on the superimposed layer by coating with material likewise passive to said etchant and also to electrolytic deposition, applying to the other face of the screen a solid layer of metal also passive to said etchant, etching away substantially all of the superimposed layer over those areas not covered by said coating until the said layer has been undercut beneath the said coating, electroplating a layer of metal over the areas exposed by the etching operation thereby adding a continuous metal layer to the surfaces delimited by the design areas, removing the coating and by means of said etchant etching the material of the superimposed layer remaining after the first etching operation and underlying the design area from which the coating has been removed, and removing the layer that has been applied to the said other face of the screen.
10. The process of producing a stencil, which comprises closing the apertures in metal screen with thin webs of metal, applying to the surface of the webs and the screen lands an unbroken heavy layer of metal active to an etchant to which the screen and the webs are passive, blocking out a design on the said heavy layer with material also passive to the said etchant, etching said heavy layer with said etchant leaving the design in relief, applying to the areas exposed by said etching operation a heavy layer of metal passive to said etchant thereby adding a continuous metal layer to the surfaces delimited by the design areas, removing the blocking-out material, etching away by means of said etchant those portions of the first-mentioned heavy layer remaining after the first-mentioned etching operation, and then removing the said webs until connecting passages are opened leading from the design areas to the rear face of the screen.
11. The process of producing a stencil, which comprises closing the apertures in metal screen with thin webs of metal, applying to the surface of the webs and the screen lands an unbroken heavy layer of metal, applying a blocking layer in the form of a design on the said heavy layer, etching said heavy layer leaving the design in relief, applying to the areas exposed by the said etching operation a heavy layer of metal, thereby adding a continuous metal layer to the surfaces delimited by the design areas, removing the blocking layer, etching away those portions of the first-mentioned heavy layer remaining after the first-mentioned etching operation, and then removing the said webs until connecting passages are opened leading from the design areas to the rear face of the screen, the etching agent employed in each etching operation being active only to the metal of the first-mentioned heavy layer.

EDWARD O. NORRIS.
